FALSE BOTTOM FOR COUNTERS

Reginald Sentenne, Westport, Conn.

Application June 4, 1940, Serial No. 338,822

1 Claim. (Cl. 312—140.3)

This application is a continuation-in-part of application Serial No. 323,085, filed March 9, 1940.

The present invention relates to display counter accessories and embodies, more specifically, a counter sham or a false bottom construction by means of which glass divider partitions may be held in desired positions on the counter.

It is common practice to utilize false bottom or sham sections that are placed upon counters with glass partitions therebetween in order to sectionalize the counter to facilitate the orderly display of wares. In order to secure sections of varying sizes, it has heretofore been necessary to maintain a considerable stock of false bottoms of various widths.

In accordance with the present invention, it is proposed to provide a false bottom construction which can be adapted to various sizes, thus avoiding the necessity of maintaining a considerable stock of all sizes on hand.

The foregoing object is attained by providing a false bottom of such construction that it may be extended or collapsed to enable it to be adjusted to a desired width.

In order that it may be more readily understood, the invention will now be described with reference to the accompanying drawings, wherein:

Fig. 1 is a perspective view, with parts broken away and in section, illustrating the manner in which the counter sham or false bottom is used in accordance with the present invention.

Fig. 2 is a bottom view showing one of the counter shams constructed in accordance with the present invention.

Fig. 3 is a view in section, taken on the line 3—3 of Fig. 2 and looking in the direction of the arrows.

Fig. 4 is a view similar to Fig. 3, showing a modified form of the invention.

Fig. 5 is a view taken on the line 5—5 of Fig. 4 and looking in the direction of the arrows.

Fig. 6 is a view similar to Fig. 3, showing a modified form of the invention.

Fig. 7 is a plan view of the modification shown in Fig. 6.

Figs. 8 and 9 are views similar to Figs. 6 and 7, respectively, showing a further modification of the invention.

Fig. 10 is a view similar to Fig. 6, showing another modified form of the invention.

Fig. 11 is a view similar to Fig. 6, showing a further modified form of the invention.

Referring to the above drawings, a counter

is shown at 10 and is provided with a horizontal supporting surface 11 upon which counter shams or false bottoms 12 are adapted to be mounted. These shams receive glass or other partition members 13 therebetween to divide the display surface into compartments or sections of suitable size and may extend as far as desired between adjacent shams. In practice, transverse partitions (not shown) may be provided between the partitions 13 to further sectionalize the display surface, but, as this is in accordance with common practice, it need not be referred to further herein.

In order that the size of the display sections may be varied as desired, and that the counter shams may be adapted to permit such variation of sizes, the present invention contemplates the use of shams having movable sections. Each section is formed with a side rail and a supporting surface, the rails of one section being shown at 14 and 15, and the respective supporting surfaces at 16 and 17, respectively. The supporting surfaces may be suitably secured to the rails and are adapted to overlap as shown in Figs. 1 and 3. In order that the supporting surfaces may be effectively positioned in overlapping relationship, the rails 14 are formed with brackets 18 and the rails 15 with brackets 19. The supporting surface 17 is received between the supporting surface 16 and the brackets 18 and, in this position, is able to support the weight placed upon the sham during use. Brackets 19 serve to reinforce and strengthen the supporting surface 17 and it will be observed that the rails 14 and 15 may be spaced variably to provide display sections of predetermined width. This is illustrated in Fig. 1 wherein three display sections are shown, each of differing width. In the form of the invention shown in Figs. 4 and 5, the sections are secured together adjustably in a modified manner. The supporting member 16 is provided with reversely turned flanges 20 at either end thereof, in order that the supporting surface 17 may be received between the respective flanges and the supporting surface 16. This provides a groove at either end of the sham and enables the cooperating elements to be secured together effectively in adjustable relationship.

In the form of the invention shown in Figs. 6 and 7, the rails 14 and 15 and their respective supporting surfaces 16 and 17 are secured together adjustably by means of rivets 21 which pass through slots 22 and 23 in the respective supporting surfaces 16 and 17. The rivets are

secured in such fashion as to permit the rails 14 and 15 to be adjusted by sliding of the rivet in the slots 22 and 23 so that the shams are maintained in a desired position through the frictional resistance offered by the rivets 21.

In the form of the invention shown in Figs. 8 and 9, the slots 22 and 23 receive bolts 24 provided with single nuts 25 to enable the shams to be secured effectively in a desired adjusting position.

In the form of the invention shown in Fig. 10, the supporting surfaces 16 and 17 are secured in a desired position by means of turn buckles 26 which are threaded on bolts 27 that pass through the rails 14 and 15. The heads of the bolts 28 are countersunk in recesses 29 formed in the respective rails.

In the form of the invention shown in Fig. 11, the sham is formed of two sections, again having supporting surfaces 16 and 17, the supporting surface 16 not only being secured to the rail 14 but also to an intermediate rail 30. The supporting surface 17 is secured to the rail 15 and

lies over the surface 16 so that it may be moved to any desired position with respect thereto.

While the invention has been described with reference to the specific structures shown in the accompanying drawings, it is not to be limited save as defined in the appended claim.

I claim:

A countersham comprising side rails, a supporting surface comprising a plurality of supporting elements, one of which is secured to one of the side rails and the other of which is secured to the other of said rails, the elements each extending laterally of its respective rail, at least one bracket carried by one of said rails and closely 10 underlying the supporting element carried by the same rail, and at least one bracket carried by the other of said rails spaced from and extending substantially parallel to the supporting element carried by the same rail to adjustably receive and 15 support the laterally extending portion of the other of the supporting elements, the brackets underlying both of the supporting elements to reinforce the same.

REGINALD SENTENNE.
